INVENTOR.

BY

Henry Deckstarr
ATTORNEY.

UNITED STATES PATENT OFFICE.

INGWALD F. RUDE, OF CHICAGO, ILLINOIS.

TOOL.

Application filed September 13, 1921. Serial No. 500,354.

To all whom it may concern.

Be it known that I, INGWALD F. RUDE, a citizen of the United States, residing at Chicago, in the county of Cook and State 5 of Illinois, have invented certain new and useful Improvements in Tools, of which the following is a specification.

My invention relates to tools and has particular reference to screw-drivers. The object of the present invention is to add greatly to the power and efficiency of the ordinary screw-driver in such a manner as to not interfere with its customary conveniences, by providing it with a lever 10 which normally forms a part of the usual handle and is quickly adjustable into its lever-operating position to increase manifold the ordinary screw-turning power where the greater resistances are 15 countered as in turning in long screws or inserting screws in hard material.

With the above named object in view my invention consists in the novel construction, combination and arrangement of parts hereinafter described in detail, illustrated in the 20 accompanying drawing, and more particularly pointed out in the appended claim.

In the drawing—

Figure 1 is a view of a screw-driver embodying my invention, with the lever in 25 closed or inoperative position, its open or operative position being shown by dotted lines.

Figure 2 is a similar view on a reduced 30 scale taken in a longitudinal plane at right angles to the plane of Figure 1 with the lever extended at right angles to its extended position in Figure 1.

In the several views 2 represents the blade 35 or bit which is shown in the present illustration with a squared shank portion 3 which is secured through the usual tang, or otherwise, to a handle 4 on which 5 represents the ordinary ferrule. To the portion 3 the lever-age 40 is applied, a lever 6 being connected therewith to normally lie parallel with the handle and to be movable at right angles thereto by either a combined sliding and angular movement as in reaching the dotted 45 line position of Figure 1, or by a chiefly pivotal movement, as in Figure 2. In the

present embodiment the connection of the lever 6 with the shank portion is a bent, lug, or, as it were, a journal portion 7 formed of one end of the lever and an elongated 55 opening 8 through the portion 3 occupied by said part 7 in either its closed or open position as in Figure 2, or by any portion of the lever 6, to lengthen or shorten it, in its dotted line position of 60 Figure 1, the extreme ends of the latter having stops 9 and 10. The lever 6 is held in its closed or inoperative position shown in full lines in Figure 1 by a moderate frictional engagement with the sides of a slot 65 or depression 11 in the side of the handle, including a hemi-spherical recess 12 adapted to receive the stop portion, or ball 10, which, like its companion stop 9, is an enlargement of the end of the lever which is made of 70 sufficient size to prevent its passage through the opening 8. The recess 11 is preferably made of a depth to receive about half of the thickness of the lever, so that only one-half of said thickness projects beyond the 75 periphery of the ordinary handle. This projection is an aid to the ordinary grip upon a screw-driver handle, and in case the blade or bit 2 should accidentally become loosened with reference to the handle so 80 as to not be normally rotatable therewith the closed lever, or the lever engaging its slot 11 seat, will serve to "key" the blade to the handle, or when disengaged from the slot and operatively extended the blade may 85 be turned by means of the lever operated with one hand while the other hand holds the handle stationary.

In the adjustment from full to dotted line positions of Figure 1 the lever is pulled 90 out of its bed or seat 11 and while being swung away from the handle slid longitudinally through the opening 8, a curved portion 13 being formed between the body of the lever and its lug portion 7 for that purpose, until said lug is out of the opening 8 and lies parallel with the handle as in its dotted line position. Thus adjusted the lever may be moved longitudinally in the opening 8 to lengthen or shorten the lever-age 95 according to the resistance to be overcome, or to adjust the lever to clear any 100

obstruction to its full length sweep or rotation.

Having thus described my invention, I claim as new and desire to secure by Letters Patent:

The combination with a screw-driver having a laterally extending opening therethrough, of a lever having a pivot portion engaged with said opening and arranged 10 at right angles to the body of said lever,

said pivot portion and body being rotatably and angularly movable in said opening, and a recess in the handle of said screw-driver in which said lever is normally held substantially parallel with the blade and handle 15 of said screw-driver.

In testimony whereof I have hereunto signed my name.

INGWALD F. RUDE.
